UNITED STATES PATENT OFFICE.

MAX. L. WEISS, OF BROOKLYN, NEW YORK.
AUTOMOBILE HOOK LATCH.

Application filed June 23, 1924. Serial No. 721,706.

Among the principal objects which the present invention has in view are: to provide latches of the character mentioned operable by a downward pressure or movement 5 in the natural direction; to maintain the active life of the latches; to render the construction adapted for the various uses in which the latches are employed; and to simplify and cheapen the construction of the 10 latches.

Drawings.

Figure 1 is a top plan view of a latch construction and arranged in accordance 15 with the present invention.

Figure 2 is a vertical section of the same the section being taken as on the line 2—2 in Figure 1.

Figure 3 is a side view of the same. 20 As seen in the drawings, the latch has an end hook 8 which is shaped to engage a catch plate 9. The catch plate 9 has a base 10 provided with perforations 11 for receiving screws for other devices for fastening a plate 25 in position on the side bar or other permanent element of the automobile structure. The hook 8 is preferably formed by compressing the extremity of the tube until the sides of the tube abut, forming thereby a two-ply 30 relatively thin structure which is shaped to the form shown in the drawings either by punching, sawing, or other convenient method.

The tube has provided therein a cut-away 35 portion or slot 12. The slot 12 is provided as a run-way for the narrow neck 13 of a bracket 14. The bracket 14 is shaped substantially as shown in Figures 1 and 3 to provide a bolting plate 15 having perforations 16 formed therein for the passage of bolts therethrough when the same is installed in 40 service on the hood of an automobile.

The bracket 14 is preferably made of sheet metal stamped to the shapes shown in the 45 drawings, particular reference being paid to the formation of the dome or globular end 17 at the extremity of the neck 13.

The globular end 17 forms a seat for one 50 extremity of the compression spring 18. The spring 18 is disposed within the tube, as seen best in Figure 2 of the drawings. One end of the spring rests against the handle 19.

The spring 18 is seated on the globular 55 end 17, as shown best in Figure 2 of the drawings, and forms thereby, and in conjunction with the globular end 17, a universal

sal bearing for the compression spring 18. The spring 18 at all times exerts a lifting tension on the tube and the hook 8. It is against this lifting tension that the force of 60 the person handling the latch is exerted, or in other words, in order to place the hook 8 in engagement with the catch plate 9, the tube has to be pressed down, the spring 18 being thereby compressed. The construction and position of the parts facilitates this action as the weight of the operator may be exerted on the handle 9 until the hook 8 is in proper position to engage the catch plate 9. The hook having arrived in this 70 position, the tube is swung upon the globular end 18 to place the hook under the overhang of the catch plate 9, as shown in Figures 2 and 3 of the drawings, the latter illustrating the position to which the hook 8 is forced when depressed in the manner referred to, while the former shows the position of the hook when engaged by the catch plate in service.

To facilitate the placement of the globular end 17, the shank 13 of the bracket, an 75 spring 18, in their relations to the tube the said tube is preferably constructed in two halves, each half being laterally extended from the handle 19. As the ends of the tube halves are drawn together to form the hook 8, the bracket 14 and the globular end 17 thereof, and the spring 18, are posed in their cooperative relation in the other half sections or extensions of the two half sections or extensions of handle 19. When the hook-shaped ends and handle 19 are disposed over the said shank 13 and globular end, the hook-shaped extremities of the said half sections are permanently joined to one another, and the globular-shaped end 17 and the spring 18 are thereafter permanently disposed in a locking relation.

From the foregoing, it will be seen when the catch plates 9 are bolted on bars of an automobile, and the brackets are bolted, riveted, or otherwise secured to the hood of an automobile in such relation to the various catch plates, the hood relation, is as follows:

The person operating the car locks the relation, is as follows: The hand upon the handle 19 and by the weight thereon compresses the tube downward and extends the tube downward all hooks 8 at the ends thereof ali

the first time in the history of the world, the people of the United States have been called upon to decide whether they will submit to the law of force, and let a single human being, or a small number of human beings, decide whether they will live or die. The people of the United States have been called upon to decide whether they will submit to the law of force, and let a single human being, or a small number of human beings, decide whether they will live or die.

the first time in the history of the world, the people of the United States have been called upon to decide whether they will submit to the law of force, and let a single human being, or a small party of men, decide whether they shall live or die. This is the first time in the history of the world that such a question has been submitted to a nation. The people of the United States have a right to decide this question for themselves, and they will do so.
